Primary Examiner — Mitchell I. Siegel*(74) Attorney, Agent, or Firm* — Banner & Witcoff, Ltd.(57) **CLAIM**

The ornamental design for a sporting implement, as shown and described.

DESCRIPTION

FIG. 1 is a top, left, rear perspective view of a sporting implement showing our new design;

FIG. 2 is a rear view thereof;

FIG. 3 is a left side view thereof; and,

FIG. 4 is an enlarged cross-sectional view taken on line 4-4 of FIG. 2.

The uneven-length broken lines immediately adjacent to the shaded area define the bounds of the claimed design and form no part thereof. The even-length broken lines depicting the remainder of the sporting implement show features that form no part of the claimed design.
